UNITED STATES PATENT OFFICE.

MILTON H. WALLERSTEIN, OF PADUCAH, KENTUCKY.

DISPLAY FIXTURE.

Application filed May 27, 1927. Serial No. 194,734.

This invention relates to improvements in display fixtures or what are more familiarly known as display racks, such fixtures being designed for displaying or exhibiting goods or articles of merchandise of various character in stores.

One object of the present invention is to provide a display fixture having a multiplicity of swiveled hangers on which the articles may be suspended for display purposes, these hangers being so constructed or designed as to prevent their telescoping one within another when they are moved on their pivotal centers.

A further object is to provide a hanger of this nature especially designed for the display of smaller articles such as neckties, said hanger having means for preventing relative movement of the ties with respect to each other when suspended on said hanger.

There are in the prior art examples of display fixtures having swiveled hangers but there does not seem to be any example of such a fixture wherein the hangers are securely attached to the fixture. The present invention, however, contemplates the provision of means for securely holding the hangers on the fixture while, at the same time, such securing means are readily removable so as to permit the hangers to be removed from the fixture or, if it is desired, to increase the capacity of the fixture by placing additional hangers on the fixture.

A further object is to provide a display fixture wherein the hangers project or extend toward one side only, the base of the fixture being proportioned and weighted in such wise as to prevent the fixture being tipped over by the weight of the hangers and goods supported thereon.

With these and other objects in view the present invention consists in certain novel details of construction and combinations and arrangements of parts all as will hereinafter be more fully described and the novel features thereof particularly pointed out in the appended claims.

In the accompanying drawings,—

Figure 1 is a front elevational view of the fixture embodying the present improvements; Fig. 2 is a side elevational view; and Fig. 3 is a top plan view; Fig. 4 is a detail top plan view of the base with the standard and struts in section; Fig. 5 is a detail view partly in section, showing the manner of holding the upper reach of the hanger in place;

Fig. 6 is a plan view of the construction shown in Fig. 5, with the hold down bar removed.

In the preferred construction of fixture, a base plate 10 is secured at its ends on a pair of supporting legs 11, said legs being provided with suitable pads 12 to prevent marring store furniture on which the fixture might be placed. The base 10 which is of metal and comparatively heavy, is located near the rear end of legs 11 and attached to said base 10 is a transversely extending metallic member 13 L-shaped in cross section. One leg of member 13 is attached to base 10 near the forward edge of the latter, and the other leg of member 13 has attached thereto a pair of standards 14 adjacent the ends of base 10. To stabilize the standards 14 they may be braced by struts 15 connected thereto and to the rear edge of base plate 10.

The standards 14 are adapted to support hangers on which the articles to be displayed may be suspended. According to the present invention these hangers are swiveled on upper and lower cross bars 17, 17^a, said cross bars being in the form of right-angled metal bars one leg of which lies parallel to the standards 14 and is connected to said standards by suitable securing elements, while the other leg lies in a horizontal plane or at right angles to said standards and is provided with a series of apertures in which the hangers are swiveled.

Due to the weight of articles placed on the hangers and on account of their being turned backward and forward to exhibit such articles, said hangers are very apt to be displaced from the apertures in the cross bars. In the present instance this is overcome by the use of additional cross bars 18, 18^a attached to said standards 14 immediately above the cross bars 17, 17^a so as to engage the swiveled ends of the hangers. Usually, the apertures in cross bars 17, 17^a are about one-half inch apart, the ordinary fixture having apertures for twenty hangers. However, a merchant's stock might be insufficient to necessitate the use of all twenty hangers so that it is desirable that he be able to readily remove as many of the hangers as it is desired. For this reason, the cross bars or hold down bars 18, 18^a are attached to the standards 14 by suitable removable fastening members such as the bolts 19 having the nuts 20 threaded thereon. By simply removing these fastening means and the bars 18, 18^a any number of hangers may be removed or, if such

hangers have been previously removed and a merchant increases his stock, the additional bars may be readily placed in the fixture by first removing the bars 18, 18^a.

5 In the preferred form of fixture the hangers project to one side only of the standards 14 so that, when the articles to be exhibited are placed on such hangers there is considerable weight on that side, tending 10 to tip the standards 14 forwardly. It is for this reason that standards 14 are arranged at the forward edge of base plate 10 and the latter is located near the rear of legs 11. This relative positioning of the several 15 portions or elements of the base effects a counter-balance of the combined weight of the hangers and the articles thereon. It should be noted that the entire construction is preferably of metal and in order to keep the cost 20 of production at a comparatively low figure the standards 14 as well as both sets of cross bars are all made of the same standard stock material.

So far as the base and standard construction is concerned, any desired form of hanger could, of course, be used. However, the hanger shown is preferred because in a hanger of this construction it is impossible for juxtaposed hangers to telescope or pass 30 one through the other. This telescoping of juxtaposed hangers is prevented by maintaining the article supporting reaches 16^a of the several hangers in substantially horizontal alinement. This preferred form of 35 hanger is composed of suitable material such as wire stock, the wire being bent to form an article supporting reach 16^a having a down-turned portion 21 at one end which is received in an aperture in bar 17. At its opposite end the article supporting reach of the hanger is connected to a lower reach 16^b, there 40 preferably being a substantially perpendicular portion 16^c intermediate the upper and lower reaches forming a hand grip 45 by means of which a person wishing to inspect the articles may grasp the hanger and turn it on its pivot. The reinforcing or lower reach 16^b extends upwardly instead of horizontally and at its lower end it is formed 50 with a downturned portion 21^a swiveled in cross bar 17^a. By having the lower reach 16^b disposed at an angle to the upper article supporting reach 16^a of the hanger and by having said upper reaches rather firmly held 55 in the cross bars 17, 18, said upper reaches cannot sag under the load imposed upon them but will always remain in substantially the same horizontal plane. In this way, it is impossible for the hangers to telescope. 60 This is quite advantageous, because, in ordinary use the series of hangers are divided at the center of the fixture and turned to the

sides thereof and when a prospective purchaser wishes to examine all of the articles on the fixture he moves the hangers, one 65 at a time, toward the center so as to bring the articles on each hanger successively in view. Having moved all the hangers formerly at one side of the fixture to the center of the latter, the hangers are then pushed 70 back to the side and, in doing this, the ordinary hangers will telescope or pass through one another so that the merchant is quite annoyed in disentangling the several hangers for future inspection. This telescoping of the juxtaposed hangers is, however, entirely old in the present instance. 75

By the use of the reinforcing lower reach 16^b of the hanger the entire hanger between the upper and lower reaches is open. The 80 hand grip portion 16^c need not necessarily be provided, although it is preferred to a construction in which the lower reinforcing reach 16^b merges directly into the upper reach 16^a. By the use of the reinforcing 85 reach 16^b the hanger is left open, so to speak, no intermediate bracing members being necessary. This naturally holds the cost of the hangers down to a minimum. In fixtures for the display of neckties and the 90 like, it is also desirable that means be provided for preventing movement of the articles longitudinally of the upper reach 16^a of the hangers. In the present instance, this is accomplished by having the upper reach 95 formed with a series of depressions 22, each of sufficient length to receive an ordinary necktie.

What I claim is:

In a tie display fixture, a pair of supports, a comparatively heavy base member extending transversely of said supports near one end thereof, a pair of standards on said base, a pair of bars of L-shape cross section mounted on said standards, one leg 100 of each bar being arranged horizontally and provided with a series of apertures therein with the other leg depending from the horizontal leg in spaced relation to said standards, a series of hangers each having upper 105 and lower reaches with a series of depressions in said upper reach for holding ties on said reach in spaced relation, each reach of each hanger having a down-turned end portion swiveled in the perforations in said 110 bars, said swiveled end portions being concealed by the depending legs of said bars, and a second pair of bars mounted on said standards above and in proximity to the first mentioned bars to prevent accidental 115 displacement of the swiveled end portions of said hangers. 120
